UNITED STATES PATENT OFFICE.

WERTER C. HIGGINS, OF NORWICH, CONNECTICUT.

STEAM AND HOT-WATER HEATER.

SPECIFICATION forming part of Letters Patent No. 537,202, dated April 9, 1895.

Application filed October 1, 1894. Serial No. 524,580. (No model.)

To all whom it may concern:

Be it known that I, WERTER C. HIGGINS, a citizen of the United States, residing at Norwich, in the county of New London and State 5 of Connecticut, have invented certain new and useful Improvements in Steam and Hot-Water Heaters, which improvements are fully set forth and described in the following specification, reference being had to the accompanying five sheets of drawings.

This invention embodies certain improvements on a sectional heater patented to me February 9, 1892, No. 468,423, which was specially and peculiarly constructed to cut 15 up the water space and present the same to the fire. Provision was also made in my said earlier heater for the free and unobstructed flow of the heated waters upward, and the 20 questions of economy and practicability in assembling the several heater sections were given due consideration.

My present invention contemplates further improvements having specially in view, first, an improved draft system whereby the caloric 25 products may be most advantageously utilized; second, certain improvements in the form of the heater sections providing a more positive and free escape for the heated waters and which also tends to produce and maintain 30 direct currents of heated water upward and of the cooler waters downward, thus avoiding conflicting currents and insuring more perfect circulation than has ordinarily been attained, and, third, an arrangement of steam 35 dome by which a steam generator of great capacity may be set up in cellars, or other places, where the "head space" is limited, thus avoiding the expense and annoyance of digging pits for such generators, as frequently practiced. 40 The drawings annexed hereto illustrate my said improvements.

Should a detailed description of the complete generator, and of the manner of assembling its various parts, be desired, reference 45 is hereby made to my said earlier patent, No. 468,423.

It is my purpose to provide a sectional ash-pit for use with the boiler sections here shown, but as said ash-pit is expected to be of the 50 form and construction shown in said Patent, No. 468,423, I have thought it unnecessary to illustrate it here. The front or "door" plate

will also be substantially the same as heretofore.

Figure 1 of the annexed drawings is a vertical section, from front to rear, of a generator embodying my present improvements, said view being taken on line $x-x$ of Figs. 2 and 6. Fig. 2 is a front face view, in elevation, of the front boiler section, that is to say 55 the section immediately in the rear of the plate to which are hung the various doors of the heater, said front section being illustrated here as made in two half parts that separate at the vertical center of the complete section. 60 Figs. 3 and 4 are respectively outer and inner edge views of one half part of said front boiler section and Fig. 5 is a cross-sectional view of the same on line $y-y$ of Fig. 2. Fig. 6 is an elevation of one of my so called intermediate 65 sections and Fig. 7 is an inner edge view of the left hand half of said section looking in the direction of the arrow. Figs. 8 and 9 are cross-sections of said intermediate section on lines 70 $y-y$ and $z-z$ respectively. Fig. 10 is an elevation of a boiler section which, if used, is located immediately at the back of the fire-pot, and Fig. 11 is an inner edge view of one of the half parts of said section. Fig. 12 is a cross-sectional view on line $y-y$ of Fig. 10, 75 and Fig. 13 illustrates the manner of producing tight joints between the adjoining boiler sections, this feature being however the same as in my earlier patent. Fig. 14 is an elevation of the rear boiler section and Fig. 15 is 80 an inner edge view of one half of said section. Figs. 16 and 17 are cross-sectional views on lines $y-y$ and $z-z$, respectively, of said rear boiler section. Fig. 18 (Sheet 1) is an elevation on a reduced scale of the rear end of the 85 heater of my improved form showing particularly the means provided for conveying the "drip," or condensed steam, from the dome. 90

In the drawings the reference figures 20 indicate the front boiler section; 21, the intermediate sections, of which any desired number may be used; 22, the rear section, and 23 a section similar to the "intermediate" but having a hollow cross-wall 23' that serves as a fire wall at the rear of the fire-pot. Section 100 23 may be dispensed with altogether or several may be used in instances in which it is desired to reduce the fire space without reducing the water space. The intermediate

sections 21, and its "fire-wall" section 23, are each formed with depending central columns 24 and inclined lateral hollow arms 25, located within the fire chamber, as in my said earlier heater, for I have found this construction to be most satisfactory in conducting the heated water to the upper part of the boiler, but I have also learned by experience that the heated water also seeks to rise in the hollow columns 26 which forms the sides of the several sections and conflicting currents are formed in said columns because of the efforts of the cooler waters to pass downward through said columns. To remedy this defect and to induce and maintain unobstructed currents of heated water upward and of the cooler water downward, I have placed in the columns 26 of each section 20—21—22—23 vertical diaphragms or plates 26^a extending downward nearly to the bottom of the columns and upward to a point somewhat below the water level. A direct passage 26^b is thus established for the downward flow of the cooler waters and I also, by preference, increase the capacity of the columns 26, (to compensate for the space occupied by the plates 26^a) by swelling, or curving outward, the outer wall of each boiler section, as at 26^c.

I have also enlarged and improved, materially, the upper portion of each boiler section by curving the side walls outward, as at 27, beginning said curves at points opposite the upper ends of the plates 26^a. (See Fig. 6.)

The hottest water in a boiler of my described construction is that within the central column 24 and the arms 25 and this water, in its efforts to rise, passes upward and is followed by the cooler waters that have simultaneously passed downward through columns 26. As the hot water passes upward it is discharged into the enlarged chamber at the upper end of each boiler section and, naturally, flows toward the curved walls 27 to fill the space vacated by the cooler waters, which latter have moved downward through the passages 26^b; the course of the water being clearly indicated by arrows in Fig. 6 of the drawings. When the hot water is discharged into the enlarged upper chamber and flows laterally, as shown and explained, it strikes the curved wall 27 and is deflected with the least possible resistance and guided by said wall in the proper direction to enter the passage 26^b without materially checking the flow of said water. By thus combining with the columns 24 and arms 25 of my old form of heater, the plate or diaphragm 26^a and the curved upper wall 27, I am able to induce and maintain a positive and constant circulation which permits the hot water to pass upward most freely and thus brings the cooler waters promptly into position to be acted upon by the fire.

It will be noticed that the sections 20—21—22—23 are here shown in two half parts, the line of junction being at the vertical center of each complete section. This construction renders it practicable to produce and assem-

ble with comparative ease, very large boilers of this class and it is also valuable in that the inner vertical walls (at the line of junction of the two half parts) preclude the formation of cross currents of water in the described enlarged chamber in the upper portion of the boiler sections. I prefer therefore to make the boiler sections in two half parts although for use in heaters of moderate size they may be a single casting as heretofore.

The steam dome of my present heater is cylindrical and is indicated by the reference figures 28. Said dome has heretofore been located above the boiler sections and connected with the latter by nipples having right and left hand threaded ends, but such construction I find is sometimes objectionable, particularly in low cellars or basements where it is frequently necessary to dig pits to receive the heater and, to overcome this objection, I have now formed each of the several boiler sections with a depression 29, in their upper central portion, of such depth that one half, or more, of the dome may be located below the highest point of said boiler sections, as seen in Fig. 2. Connections are then made with the two half parts of each of said boiler sections by means of threaded nipples 30 which allow steam to pass from the several boiler sections into the dome.

To remove the "drip" which accumulates by condensation in the dome 28 a pipe 31 is tapped into said dome at its rear end and connected with branch pipes 32—33 that lead into manifold pipes 34—35 that connect the lower portions of the boiler sections and provide for free circulation of the water from section to section.

I have improved the draft system of my heater in a noticeable degree by utilizing more completely the caloric products of combustion than was possible in my earlier form of heater, in which the draft flues led from the rear of the combustion chamber toward the front of the heater and discharged directly into the smoke pipe. In this present heater a second system of flues 36 is provided, immediately over the first mentioned, by which the products of combustion are caused to travel again the entire length of the boiler and discharge into a smoke pipe 37 at the rear of said boiler. Of course I do not seek to claim broadly a return flue, or duplex system of flues, for this class of heaters, but I find that, when combined with the water columns 24 and inclined arms 25 which are immediately in the fire-pot, and receive the direct action of the fire, the said flues aid materially in reaching and influencing the waters that are beyond such direct action of the fire and a marked economy of fuel is the result.

In the intermediate boiler sections 21—23 the upper horizontal draft openings are indicated by the figures 38 and are three in number for each half section while those of the front and rear sections have but a single

large opening for each half section, this difference of construction being desirable in order to provide an unobstructed passage and chamber for the turning of the smoke, &c., at 5 the front and for the free discharge of the same at the rear of the heater.

Having described my invention, I claim as new and wish to secure by Letters Patent—

1. In a generator, in combination with the front and rear sections, a multiple of intermediate sections having central vertical water columns connected by inclined lateral pipes with the hollow vertical sides of said sections, said hollow sides having diaphragms 15 26^a as set forth and being also formed with laterally enlarged upper portions 27, substantially as and for the purpose specified.

2. In combination with front and rear boiler sections, a multiple of intermediate sections

having vertical water columns connected by 20 inclined pipes with the hollow vertical sides of said sections, each section being formed of two half parts that are separable at the vertical center of the complete section, substantially as specified. 25

3. In a generator, a multiple of connected boiler sections, each formed with a depression 29 as set forth, a steam dome located in said depressions, steam connections between said dome and boiler sections, manifold pipe connections 34 35 at the sides of said boiler sections, and a drip pipe connecting said dome with said manifold pipes, substantially as specified. 30
